UNITED STATES PATENT OFFICE.

SAMUEL ABBOTT, OF CLEVELAND, OHIO, ASSIGNOR TO THE GLOBE MACHINE & STAMPING COMPANY, OF CLEVELAND, OHIO.

MACHINE FOR FORMING BOX-BODIES AND THE LIKE.

1,323,143.

Specification of Letters Patent.

Patented Nov. 25, 1919.

Application filed April 23, 1917. Serial No. 163,796.

To all whom it may concern:

Be it known that I, SAMUEL ABBOTT, a citizen of the United States, residing at Cleveland, in the county of Cuyahoga and State of Ohio, have invented a certain new and useful Improvement in Machines for Forming Box-Bodies and the like, of which the following is a full, clear, and exact description, reference being had to the accompanying drawings.

This invention relates to a machine for forming box bodies and the like, and has for its objects the production of a substantial and durable machine of this character that is susceptible to a wide range of adjustments thus readily lending itself to the making of articles of various sizes; the provision of simple means of quickly and accurately determining and positively maintaining the adjustments; the production of a machine of the foregoing character that is rapid of operation; convenient of use; and wherein a blank is given a succession of gentle bends from its center toward its ends, thereby allowing the metal to adjust itself to the new configuration without disturbing its integrity.

Other objects are the inclusion, in a machine of the above nature, of simple means for properly locating the blank within the machine; and the employment of a control through which the action of the machine may be suspended upon a completion of the forming operation and before the article is released to hold the ends of the blank in proper relation to each other for joining.

The foregoing objects, and others which will become apparent as this description proceeds, are attained in an embodiment of the invention illustrated in the accompanying drawings wherein Figure 1 is a plan view of the machine; Fig. 2 is a rear elevation, the machine being turned end-for-end in this figure with respect to the position it occupies in Fig. 1; Fig. 3 is a vertical section through the machine on the line 3—3 of Fig. 2 and looking in the direction of the arrows; Figs. 4, 5 and 6 are sectional details on the line x—x of Fig. 3, the three views representing, respectively, three successive steps in the operation of the machine; Fig. 7 is a horizontal section on the line 7—7 of Fig. 4, the plane of section being substantially coincident with that of the table top; Fig. 8 is a sectional detail on the

line 8—8 of Fig. 2, showing the clutch; Fig. 9 is a fragmentary perspective view of the blank from which a box body is formed; Fig. 10 is a similar view of the formed box body; and Fig. 11, a like view of one of the machine elements, known herein as a riser.

The frame of the machine is made up of the end members 1 and 2 which are rigidly connected at their upper ends by the front 65 and rear longitudinal members 3 and 4, respectively. The members 3 and 4 are of angular formation, their vertical flanges being attached to the end members by the bolts 5, and their horizontal flanges constituting 70 what I shall term, for convenience, the table of the machine. Entering into the makeup of the frame are transverse members 10, having end plates 11, which bear against the inner sides of the vertical flanges of the 75 longitudinal members 3 and 4, and which are clamped thereto by bolts 12 passing through holes in the end plates and slots in the flanges, thus providing an adjustment of the members 10 longitudinally of the 80 machine.

The horizontal flange of the member 4 has longitudinal slots 15 through which bolts 16 pass for clamping, in various adjusted positions therealong, the rearward 85 extensions 17 of the lower corner members 18 of a form 20. The form further comprises upper corner members 21 which have depending sides that overlap side portions of the corner members 18 and are attached 90 thereto, as by bolts 22. The opposed upper corner members 21 are connected together and spaced apart a definite distance by bars 23, and the forward ends of the opposed lower corner members are likewise connected and spaced apart by a bar 24. Templets 25 and 26, having curved outer surfaces, are shown as mortised within the corners of the members 18 and 21, respectively, and are held in place by bolts 27. In the 100 action of the machine the blank is bent upward and about the form 20, and, to withstand the upward thrust of the forming dies, I employ a tension member in the form of a jack-screw 30, which passes upward between 105 parallel plates 31, extending between the opposed flanges of the members 3 and 4 and have their ends turned outward for attachment to said flanges by bolts 32. The jack-screw is provided with a suitable abutment 110

for engagement with the lower edges of plates 31, and at its upper end carries a cross-bar 35, adjustable freely along the screw and held against upward movement by 5 the nut and washer 36 and 37, respectively. Thrust blocks 38 are applied to and adjustable along the ends of the bar 35 and their lower ends engage the corner members 21 of the form.

10 A block 40, having a dovetail groove along its upper side, is secured to the front member 3, at about its longitudinal center, and a dovetail slide 41 is adjustable within the groove of the block transversely of the machine, and the slide may be held in any adjusted position by a set screw 42. A gage point 43 rises from the rear end of the slide, and its purpose will be presently explained.

At the front and rear corners of each of 20 the transverse frame members 10 are a pair of ears 45 (see Fig. 7) between which are pivoted, upon pins 46, arms 47 (see Figs. 4 to 6). Adjustable along the free ends of the arms 47 are the ends of a plate 50, the 25 plate being provided with hollow bosses 51 for the reception of the ends of the arms and set screws 52 are threaded through the walls of the bosses for clamping the plate in various adjusted positions. It will be seen that 30 each pair of arms 47 and the respective plate 50 constitute a frame which is pivoted to one of the transverse members 10 so that the frame is capable of swinging upward alongside the adjacent end of the form 20. To 35 the upper or outer edge of each plate 50 is hinged a plate 55, the pintle of the hinge being represented at 56. Springs 57 are coiled about each end of the pintle, as shown particularly in Figs. 1 and 2, and their ends 40 are connected to the respective plates. Because of the direction in which they are wound, and the disposition of their ends, the springs tend to maintain the plates 50 and 55 in a common plane. The plates 55 have 45 extensions 58 which normally extend over and engage the under or outer sides of the plates 50. Heads 60, which are adjustably connected to bumpers 61, are pivotally connected to the lower or inner ends of the 50 extensions 58, and the pivoted ends of the heads are squared and abut the adjacent surface of the plates 50, when the parts are in normal condition, so that the bumpers are held in planes substantially parallel to the 55 plates 50.

Guided between the inner face of each transverse frame member 10, and guide plates 65 applied thereto, is a riser 66. Each riser has an enlargement 67 at its upper end 60 which normally rests upon the frame member 10, and side extensions 68 of the enlargement repose beneath the previously mentioned arms 47 and have anti-friction rollers 69 for engagement with said arms. 65 Therefore, as the risers ascend, their rollers

69 traverse the edges of the arms and swing the frames consisting of the arms 47 and plates 50 upward, the rollers passing first along the inclined edges and then along the straight edges of lateral extensions 47^a of 70 the arms 47, all of which is clearly illustrated in Figs. 4 to 6. Pivoted upon pins 70, having their ends supported in plates 70^a that are attached to the opposite sides of the lower socketed ends of the risers 66 are 75 the upper ends of straps 71 of eccentrics 72 which are splined upon a shaft 73, journaled within bearings 74, carried by the end members 1 and 2, the shaft being supported intermediate its ends by a bearing bracket 75. 80 The eccentrics may be secured in various adjusted positions along the shaft by set screws 75, the inner ends of which are adapted to enter recesses 76. Formed integral with and upon the inner side of each of the eccentrics 72 is a cam 77, over which a fork 78 engages and has journaled within it, upon a pin 79, a roller 80 that is arranged to traverse the cam. The fork is adjustably connected to a yoke 82, the upper ends of 85 which are guided within bearing blocks 83 that are secured, by means of bolts 84, to a beam 85 which, as will be seen upon referring to Fig. 7, is attached to the adjacent transverse frame member 10 by the outer 90 ones of the aforesaid bolts 84, the beam having clamped between itself and the transverse frame member, the guide plates 65 previously referred to. A head 88 is secured, by screws 89, to the upper end of each 100 of the yokes 82, and hinged to the upper outer corner of each head 88 is a plate 90, the hinge pintle being designated 91. Within the upper faces of the heads 88, and within the plates 90, 50, and 55, are secured die 105 members 100 which are adapted to coöperate with the templets 25 and 26, in the formation of the corners of the box body, the dies having curved faces complementary to the curved faces of the templets. Rollers 101 110 have their gudgeons journaled within ears 102 rising from the ends of the risers 66, and are thus supported in a position to engage and ride along the under or outer surfaces of the plates 90, when the riser ascends. Hardened abutments 103 are carried by the risers for engagement with the bumpers 66, as will be made clear in the description of the operation of the machine. 115 To more rigorously confine the risers to their paths of movement, I employ for each two guide rails 105 and 106. The former is located adjacent the forward end of the riser and is connected thereto by screws 107, the rail depending alongside the frame member 10 and guided between plates 108, applied thereto, so that the rail 105 ascends and descends with the riser. The lower end of the rear rail 106 is secured, by screws 109, to the frame member, and its upper end 120

is confined between guides 110 that are carried by the riser.

Reposing upon the rear extensions 17 of the form members 18 are housings 112 within the perforated ends of which are guided plungers 113 that are impelled, by the springs 114, toward the ends of the machine and in a plane to engage the arms 47 when they are swung upward. These 10 plungers, therefore, tend to initiate the downward movement of the arms after they have performed their function in the box forming operation. Springs 115, anchored to a part of the machine, overlie the rear 15 ends of the plates 90 and tend to hold them in a horizontal position. To counterbalance each frame comprising the arms 47 and plate 50, I employ a weight 118 which is suspended upon cable 119, passing over 20 sheave 120 and having its end connected, at 121, to the rear arm 47, near its pivoted end. Thus the mechanism which operates the risers 66 is relieved of unnecessary work. The sheaves 120 are journaled upon stub 25 shafts carried by the upper ends of brackets 123 which bear, at the lower ends, upon the rear longitudinal frame member 4. Each bracket is adapted to be clamped at various 30 adjusted positions along the frame member by means of a bolt 124 which passes through the base of the bracket, beyond the edge of the horizontal flange of the frame member, and through a clamping plate 125, bearing 35 against the underside of the flange and having its outer end turned upward for engagement with the base of the bracket. This construction is clearly revealed in Fig. 2.

A spur gear 130 is secured to the shaft 73, adjacent the end member 1, and meshes 40 with a pinion 131 that is fastened to a shaft 132. This shaft has its inner end journaled within a bearing formed in the lower end of a bracket 133 that depends from the rear frame member 4, and is supported near its 45 outer end, within a bearing 135 applied to the frame member 1. Beyond the bearing 135, the shaft 132 has keyed to it a clutch element 136 for coöperation with a clutch member incorporated within the hub of the 50 pulley 138 that is loosely mounted upon the end of the shaft 132. This clutch is of an ordinary type and involves a plunger 139, which enters a notch 140 in the hub of the pulley, the plunger being forced 55 toward the hub by a spring 141, and the end of the plunger adjacent the spring has a lateral extension 142 for coöperation with a trip plate 143 that is secured to the upper end of a rod 144. The rod is guided within 60 a suitable bracket 145 that extends from the frame member 1 and a spring 146 tends to elevate the rod, and consequently the trip plate, the latter into the path of the lateral extension 142 of the plunger. The lower 65 end of the rod 144 has connection, through

the links 148, with the forward end of an arm 149 that is shown as consisting of the forwardly turned end of a rock shaft 150 that is journaled within standards 151 and 152. A foot lever 153 is pinned to the end of 70 the shaft remote from the arm 149 and projects forwardly at about the center of the machine in convenient reach of the operator, the foot lever being guided adjacent its forward end within a loop 155, rising from 75 the floor.

A sheet metal blank A from which a box body is to be formed, is shown in Fig. 9, and one of its longitudinal edges is turned laterally to form a flange a . Where the 80 corners of the box body are intended to be formed, the flange is notched, as indicated at a' , for the obvious purpose of allowing the flange to conform to the shape given the corner without crimping or buckling. At its longitudinal center and adjacent its edge remote from the flange a , the blank is provided with an aperture a^2 which, in the completed box, may serve as 85 a key-hole. 90

In the operation of the machine, the blank is inserted beneath the form until its flange a engages the front surface of the lower corner members of the form, and its position longitudinally of the machine may be 95 determined by arranging its opening a^2 in register with the gage point 43. The operator then presses the foot lever 153, rocking with shaft 150 and withdrawing, by reason of its previously described connections with the trip plate 143, said plate from engagement with the lateral extension of the plunger 139. Instantly the plunger is projected, by the spring 141, into effective position to enter the notch 140 of the pulley hub as soon 100 as the notch moves into register therewith, it being understood that the pulley is continuously driven through a suitable belt (not shown). Power is now transmitted through the shaft 132, pinion 131, and gear 130, to 105 shaft 73. Upon the rotation of this shaft, the heads 88 are elevated to clamp and form the metal between the die members carried by said heads and the lower portions of the templets 25. Simultaneously with the elevation of the heads 88, the risers 66 begin to 110 ascend through the action of the eccentrics 72. The rollers 101, carried by the risers, engage the plates 90 and swing them upward upon their hinges to present the die 115 members carried by these plates into operative relation to the remaining portions of the templets 25, thereby completing the formation of the lower corners. The continued ascent of the risers 66, through their rollers 120 68, swings the arms 47 and plates 50 upward, forcing their die members into firm engagement with the portions of the templets 26. The parts are shown in this condition in Fig. 5. At this point in the oper- 130

ation of the machine, the bumpers 61 repose above the abutments 103 of the risers, so that upon further elevation of the risers the bumpers are forced upward to swing the plates 55 over upon their hinges to present their die members into operative relation with the remaining portions of the templets 26, thereby to complete the formation of the upper corners of the box body. Here 10 the action of the machine may be stopped by the release of the foot lever 153, so that the overlapping ends of the blank may be connected, as by spot welding. At this stage the cams 77 and the eccentrics 72 are in their 15 highest positions. Therefore, by again rendering the clutch effective by the depression of the foot lever, the eccentrics and cams may continue to rotate as before to normal position to return the parts to the positions 20 shown in Figs. 1 to 4; when the formed box body may be removed from the machine.

Shorter or longer bars may be substituted for the present bars 23 and 24, in the production of boxes of various lengths; and to 25 produce wider or narrower boxes, deeper or more shallow upper corner members, respectively, may be substituted for the present corner members 21; In thus changing the size of the form, the thrust blocks 38 and 30 bar 35 are moved accordingly. Corresponding 35 adjustments are made throughout the box forming parts of the machine, the manner of making the adjustments being obvious from the constructions above described. It may be stated, however, that for different length boxes, the risers 66, and all parts associated therewith including the eccentrics and cams, may be moved as single units. To facilitate properly locating and 40 maintaining in position the various adjustable parts, tapered pins 160 are insertible through holes 161 of a series in each end of the vertical flanges of the members 3 and 4 and into holes in the end plates of the trans- 45 verse frame members 10; similar pins 163 are carried by the rearward extensions 17 of the form members 18 and are adapted to have their lower ends placed in holes 164 in the horizontal flange of the rear frame mem- 50 ber 4; and pins 166 may be inserted through holes in the bosses 51 of the plates 50 into various ones of a series of holes 167 in the arms 47.

Having thus described my invention, 55 what I claim is:—

1. In a machine of the character set forth, the combination of a form, a head movable toward and in a fixed path with respect to said form, a die carrier hinged to said head, 60 a frame pivotally supported in operative relation to the form, a die carrier hinged to said frame, dies carried respectively by the head, the frame and the first and second die carriers, means for moving the head to 65 present its die to a portion of the form, and

further means arranged to engage the first die carrier and the frame and movable to swing said carrier and frame into a position to present their respective dies to portions of the form, and operative connections be- 70 tween said means and the second die carrier for swinging said carrier to present its die to a portion of the form.

2. In a machine of the character set forth, the combination of a form, a head movable 75 toward and from a portion of the form, a die member hingedly connected to the head, a frame including a die member pivotally supported in operative relation to the form, a die member pivotally connected to the free 80 side of the frame, bumpers having operative connection with the last mentioned die member, means for moving the head toward and from the form, and a member reciprocable in a fixed path with respect to the head and 85 arranged to engage and swing the first mentioned die member and the frame toward the form and having a part for engagement with the aforesaid bumper for swinging the remaining die member toward the form. 90

3. In a machine of the character set forth, the combination of a rectangular form frame, templets incorporated in corners thereof, a head located adjacent each end of the form frame and movable in a plane sub- 95 stantially parallel to said end toward and from a corner templet of the frame, a die carried by each head for coöperation with a portion of the adjacent templet, a shaft, means for rotating said shaft, operative connections between said shaft and the aforesaid heads, die carrying members pivotally supported in operative relation to the ends of the form, dies carried thereby for coöperation with further portions of the aforesaid 100 templets, a member adjacent each head and reciprocable in a plane substantially parallel to the plane of movement of the head and arranged to engage and swing said die carrying members into effective positions 105 with respect to the form frame, and operative connections between said members and the shaft.

4. In a machine of the character set forth, the combination of a supporting structure, 115 a form of alterable size surmounting the same, a pressure element supported by the structure beneath the form, power mechanism for moving said element into operative relation to the form, and a thrust element 120 rising from and adjustable with respect to the structure for backing up the form.

5. In a machine of the character set forth, the combination of a supporting structure, 125 a form surmounting the same, a head sup- ported by said structure beneath the form, power mechanism for moving said head into operative relation to the form, a tension member rising from the supporting structure and extending above the form, a thrust 130

bar carried by said tension member, and thrust blocks between said bar and form.

6. In a machine of the character set forth, the combination of a supporting structure, a form of alterable size surmounting the same, a pressure element supported by the structure beneath the form, power mechanism for moving said element into operative relation to the form, a tension member rising from the structure and extending above the form, a thrust bar adjustable along said member above the form, and thrust blocks adjustable along the bar and interposed between said bar and form.

15 7. In a machine of the character set forth, the combination of a table, a form supported by and above the table and having connection therewith at the rear side of the table, die members pivotally supported adjacent the ends of the form, members supported by the table for coöperation with the die members and reciprocable in vertical planes adjacent each end of the form, thereby to swing the die members into operative relation to the form, a rail having its upper end secured to the forward side of each reciprocable member, the table having a way within which said rail is guided, a second rail having its lower end secured to the table adjacent each of the reciprocable members and extending above the table, each of said members having a guideway which traverses said rail, and mechanism for actuating the reciprocable members.

35 8. In a machine of the character set forth, the combination of a supporting structure, a form of variable size surmounting the same, an element located adjacent each end of the form and adjustable longitudinally of the structure, a shaft supported longitudinally of the structure beneath said elements, a vertically movable head supported by each element beneath the adjacent end of the form, a series of die members pivotally supported by each element in operative relation to the form, a member reciprocable within each element for engaging and swinging the

die members into effective position, a driving member adjustable along the shaft beneath each of the aforesaid elements, operative connections between said driving member and each head and reciprocable member located thereabove, and means for rotating the shaft.

50 9. In a machine of the character set forth, the combination of a form adjustable to vary its size, a forming element adjustably mounted thereto and pivotally supported in operative relation to the form, means for swinging said element toward the form, and further means rendered effective as the element approaches the form for initiating the return movement of the element.

55 10. In a machine of the character set forth, the combination of a supporting structure, a form supported thereby, a forming device pivotally supported in operative relation to the form, means for swinging said device toward the form, a guide carried by the supporting structure adjacent said device, a flexible element attached to the forming device and engaged over the guide, and a counterweight connected to said element for assisting in the swinging operation of the forming device.

65 11. In a machine of the character set forth, the combination of a supporting structure, a form of variable size supported thereby, a driving element, a unit supported by the structure and adjustable to compensate for the various sizes of the form, said unit comprising forming mechanism for coöperation with the form and operative connections between said mechanism and the driving element, the supporting structure and unit having one an aperture and the other a series of holes with the respective ones of which the aperture may be caused to register, and a locating device adapted to occupy said aperture and one of said holes.

70 75 80 85 90 95 In testimony whereof, I hereunto affix my signature.

SAMUEL ABBOTT.
